UNITED STATES PATENT OFFICE

2,412,316

FUEL INJECTION SYSTEM

John F. Campbell, Detroit, Mich., assignor to
George M. Holley and Earl Holley

Application January 16, 1942, Serial No. 426,977

4 Claims. (Cl. 103—37)

1

The object of this invention is to inject volatile fuels or fuels containing air bubbles by means of a plunger into an internal combustion engine. The specific object is to permit the bubbles of air and vapor to escape before injection of the fuel without interfering with the metering characteristics of the fuel injection pump. In fuels of the volatile type it is customary to use spark ignition and therefore, the time of ignition is not determined by the time of the fuel injection. With such pumps, I have found that it is desirable to have a fixed point of cut-off prior to the ignition point and therefore, I regulate the amount of fuel by the variable point in the pumping stroke of the pump when the escape of the surplus fuel and fuel carrying the vapor is prevented. As the plunger moves beyond the initial point the fuel is injected into the engine cylinder until the fuel pressure is suddenly released.

In the drawings:

Fig. 1 shows diagrammatically the arrangement of all the elements of my invention.

Fig. 2 shows the principal element—the fuel pump—on a section of plane 2—2 of Figs. 3 and 7.

Fig. 3 is a cross sectional plan view taken on plane 3—3 of Fig. 2.

Fig. 4 is a plan view taken on plane 4—4 of Fig. 2.

Fig. 5 is a plan view taken on plane 5—5 of Fig. 2.

Fig. 6 is a plan view taken on plane 6—6 of Fig. 2.

Fig. 7 is a plan view taken on plane 7—7 of Fig. 2.

Fig. 8 is a sectional elevation of a modification of Fig. 2.

Fig. 9 shows a cross sectional elevation of the vapor separator.

Fig. 1 shows diagrammatically the arrangements of the parts. Fuel leaves a tank 10 and is raised by a pump 11 to the fuel/air mixture ratio control 12 which contains a fuel venturi 13. The fuel flows through a second venturi 14 to the vapor separator 15 whence it continues through a pipe 16 to the fuel entrance 17 of the metering pump 17. Here a minor portion issues into a chamber 18 where the vapor rises to the upper part of this chamber 18. The major portion of the fuel discharges through the outlets 19. The minor fraction of the fuel in the chamber 18 is recirculated through the opening 20 into the throat of the venturi 14 back to the vapor separator 15. This recirculation of the fuel ensures the elimination of entrained bubbles which disturb the metering characteristics of the pump. The venturi 13

10 shown in the upper right hand corner of Fig. 1 is shown on a greatly enlarged scale but is actually of the same order of magnitude as the venturi 13 and has merely been enlarged so as to clearly indicate the nature of the restriction 13 which corresponds to the venturi 13 as shown in my Patent No. 2,281,411, Fig. 12. In Fig. 12 of this patent, the venturi 13 is also shown in a large scale for a like reason.

15 Considering the details shown in Figs. 2 to 7, 16 is the fuel entrance as mentioned above, which delivers fuel to the cylinders 19. In these cylinders are two diametered plungers 20 reciprocated by the inclined swash plate 21 (Fig. 2) by means of the oblate spheroid 22 of the plungers 20. Each plunger has a tubular extension 23 of a smaller diameter than the main piston 20. Each of these tubular extensions 23 engages with a movable yieldable abutment 24. Each of these 20 yieldable abutments 24 is loaded by two springs 26 and 27. These springs are located in a chamber 24 and seat on a flange 25 which, in its turn, seats on the movable abutment 24. The abutments of the springs are carried in a cage 28, on 25 the lower flange of which the abutments 24 seat when the tubular extension 23 of the piston 20 is withdrawn into the cylinder 19, as shown on the left hand side of Fig. 2. On the right hand side of Fig. 2, the piston 20 is shown elevated carrying 30 with it the tubular extension 23 which thus compresses the springs 26, 27 by engaging with and moving the movable abutments 24.

The cage 28 is reciprocated relative to the cylinders 19. Means for reciprocating it consists of a 35 lever 29 which rotates the shaft 40 which engages with the shaft 41. Grooves 39 are provided on shaft 41 adapted to move the pins 34, 35 which are mounted on the cage 28. The cage 28 is thus moved when the shafts 40 and 41 are rotated compressing the springs 27 and 26. The spring 39 balances in part the resistance of these springs 26 and 27.

40 The rotation of the lever 29 thus determines the effective length of the stroke of the two diametered plungers 20 when their tubular extensions 23 engage with the movable abutments 24 which is the moment when the plunger 20 starts to deliver fuel to the nozzle, assuming that the piston 20 has covered the port 58 before the part 23 engages 50 with the part 24.

The tubular extension 23 is perforated so that as the plunger 20 moves towards the movable abutments 24 any fuel containing air which is trapped in the annular portion between the tubular extension 23 and the walls of the cylinder

19 discharges through the center of the tubular extension 23 and along the flutes of the guide to the valve 24 which centers the valve 24 inside the central passage through the tubular extension 23. The moment the fuel is trapped in the cylinder 19, that is, the moment the tubular extension 23 engages with the movable abutment 24, fuel is subjected to pressure and in Fig. 4 is shown a number of spring-loaded check valves 32. Fuel then discharges through the passages 33 and flows down to the outlet passages 18, whence it is led to the nozzles on the engine (not shown). Now the chamber 34 which contains the springs 26 and 27 and the cage 28 communicates with the throat of the venturi 14 (Fig. 3), through a passage 35 whence it is carried to the vapor separator 15 (Fig. 3).

The fuel surrounding the springs 26 and 27 is agitated by the reciprocation of these springs, bubbles of vapor are released and these bubbles 20 escape through the venturi 14 located above the chamber 34.

The piston 20 is provided with a number of small holes 7 communicating with an annular passage 60 which has an outlet port 57 and when this port 57 rises, as shown on the right hand side of Fig. 2, it is in alignment with the cylinder port 58 and the discharge of the fuel abruptly ceases, the fuel escaping into the annulus 42.

In Fig. 8, the pump elements 20, 23 of Fig. 2 are modified as follows: The part 50 of Fig. 8 corresponds to the part 20 of Fig. 2 and the part 22 corresponds to and is identical with the part marked 22 of Fig. 2. The plunger 50 has a valve seat 51 which engages with a coned valve surface 52 which forms the lower end of a small piston 53. In the center of this small hollow valve is a passage 54 through which fuel can freely discharge before valve 52 seats on valve seat 51. The small hollow valve 53 carries the collar 55 which seats on the shoulder 28 and this collar 55 is compressed against the shoulder 28 by the springs 26, 27, and the element 25 of Fig. 2, which it is not necessary to show again as the function is the same. This shoulder 28 as already described can be moved by means of the pins 31, 31 and the slots 30, 30. Hence the small hollow valve 53 forms a variable cut-off for the piston 50. A bushing 56 forms a bearing for the small piston 52.

An annular opening 57 in the piston 50 is connected by a number of small holes 59 to the top face of the piston 50. The result is that the small holes 59 serve as a by-pass so that when the piston 50 has completed its stroke and the annular opening 57 is in alignment with the annular port 58 of the cylinder, the discharge of the fuel abruptly ceases.

In Fig. 9, the vapor separator 15 is shown in greater detail. The surplus fuel enters the venturi 14 through the entrance 35, leaves through the passage 61, and then past the baffle 62 into the float chamber 63 in which a float 64 carries a slide valve 65 which permits air and vapor to escape through the outlet 66. The fuel thus freed from vapor escapes past the screen 67 into the outlet 68 and then through a pipe 69 to the entrance 16. Of course, the vapor separator 15 can be built as an integral part of the upper casing 35 of the fuel pump.

Operation

The device is mounted so that the venturi 14 is located above the vapor separating chamber, that is to say, whether the device shown in Fig. 2

5 is either vertical or horizontal, it is arranged so that the venturi 14 is on the top side of the vertical or horizontal pump chamber. As the pump operates, any bubbles that may collect in the chamber 34 are automatically removed to the vapor separator 15 by means of the venturi 14. When the engine develops over 50% of its power, the amount of fuel flowing through the passage 35 is 20% or more of the total quantity of fuel that enters the fuel entrance 16. Hence this portion of the fuel is re-circulated and carries with it the bubbles of vapor and air to the vapor separator 15. By this means the cylinders are maintained full of fuel so that the amount of fuel discharged by each nozzle is uniform, and the vapor ceases to be an objectionable feature as it is largely removed through the vapor separator 15.

10 The effect of the re-circulation of a portion of the fuel is that the fuel admitted first to the pump chamber, that is the fuel which enters into a partial vacuum and is most likely to release vapor bubbles, is rejected through the passage 54 (Fig. 8) and past the valve 24 (Fig. 2).

15 The reason the fuel flows into the chamber 34 and not back into the annular chamber 42 is because the pressure in the chamber 34 is maintained below the pressure in 42 by means of the venturi 12.

20 The mode of operation of the modification shown in Fig. 8 and that of the device shown in Fig. 2 is substantially identical. In both cases, the escape of fuel into the chamber 34 is abruptly terminated when the cut-off valve seats and thereafter the fuel is compressed and discharged into the cylinder until such time as the groove 57 in the plunger is in line with the annular groove 58 in the cylinder which determines the end of the injection stroke.

25 In the construction shown in Fig. 8, fuel enters from the annulus 42 and is first rejected through the passage 54 and a portion of the fuel is then trapped between the piston 50 and the piston 53 when the valve seat 51 engages the hollow valve 53 having a seat 52. This portion of the fuel which is thus trapped is then injected through a passage corresponding to the passage 33 of Fig. 2, until such time as the slot 57 comes into alignment with the annular passage 58 when the pressure is suddenly and completely released. It follows, therefore, that as the valve seats (51 in Fig. 8 and 24 in Fig. 2) are moved back and forth by the rotation of the lever 29, the time at which injection commences varies, but there is a fixed 30 point of cut-off determined by the instant when the slot 57 in the plunger comes into line with the cylinder port 58.

35 What I claim is:

40 1. In a fuel injection system for an internal combustion engine, a supply of fuel under pressure, a vapor separator, a vapor separating tank, a pump chamber, a fuel entrance communicating with said fuel supply and leading to said vapor separator and communicating with said separating tank, a fuel outlet from said separator forming the entrance to said pump chamber, means for maintaining a lower pressure in the separating tank than in the fuel entrance to the pump chamber, a plunger, means for reciprocating said plunger, a valve seat integral with said plunger, a hollow cylindrical valve in alignment with said seat of smaller diameter than said plunger and adapted to permit surplus fuel to flow through it to said separating tank, means for moving said valve so as to engage with said valve seat at

different points in the stroke of said plunger so as to interrupt the release of surplus fuel, yieldable means to permit the valve to move with said plunger after it has seated thereon, a relief passage in said plunger, a relief port in the side of said plunger, an inlet port to the cylinder adapted to engage with the relief port in said plunger towards the end of the pressure stroke of the pump, and also adapted to be uncovered by the end of the plunger when it is near the end of its suction stroke, an outlet port from the cylinder, a check valve therein, whereby the plunger on its down stroke first uncovers the inlet ports and thereby permits fuel to flow through the cylinder and past the valve to the separating tank under the pressure difference between the separating tank and the fuel entrance and whereby after this port is covered by the plunger on its in stroke, fuel is then forced past the valve to the separating tank and whereby after the plunger engages with the hollow valve fuel is trapped and thereby ejected through the outlet port past the check valve and this discharge continues until the relief port of the plunger engages with the inlet port of the cylinder when the discharge of fuel is abruptly terminated.

2. In a device as set forth in claim 1 in which the means for maintaining a lower pressure in the separating tank consists of a venturi in the fuel line and an opening in the throat of the venturi communicating with the separating tank so as to return the surplus fuel to be re-circulated.

3. In a fuel injection system for an internal combustion engine, a supply of fuel under pressure, a vapor separating tank, a vapor separator, a pump chamber, a fuel entrance communicating with said fuel supply and leading to said vapor separator and communicating with said separating tank, a fuel outlet from said separator forming the entrance leading to said pump chamber, means for maintaining a lower pressure in the separating tank than in the fuel entrance to the pump chamber, a plunger, means for reciprocating

ing said plunger, a hollow cylindrical extension of said plunger having a valve seat in the end, a valve engaging with said valve seat and in alignment therewith and adapted to permit surplus fuel to flow from the pump chamber to the separating tank, the diameter of said cylindrical extension being less than the diameter of said plunger, adjustable means for locating said valve so that it engages with said extension at different points in the stroke of the plunger, yieldable means permitting the valve to move with said extension after it has seated, a relief passage in said plunger, a relief port in the side of said plunger, an inlet port to the cylinder adapted to engage with the relief port in said plunger toward the end of the pressure stroke of the pump and also adapted to be uncovered by the end of the larger diameter of the plunger when it is near the end of its suction stroke, an outlet port from the cylinder, a check valve therein, whereby the plunger on its down stroke first uncovers the inlet ports and thereby permits fuel to flow through the cylinder and through the hollow valve to the separating tank under the pressure difference between the separating tank and the fuel entrance and whereby after this port is covered by the plunger on its in stroke, fuel is then forced through the hollow valve to the separating tank and whereby after the extension of the plunger engages with the valve fuel is trapped and thereby ejected through the outlet port past the check valve and this discharge continues until the relief port of the plunger engages with the inlet port of the cylinder when the discharge of fuel is abruptly terminated.

4. In a device as set forth in claim 3 in which the means for maintaining a lower pressure in the separating tank consists of a venturi in the fuel line and an opening in the throat of the venturi communicating with the separating tank so as to return the surplus fuel to be re-circulated.

JOHN F. CAMPBELL.
